GARMENT

Daniel B. Fisher, Los Angeles, Calif.

Application April 11, 1938, Serial No. 201,394

3 Claims. (Cl. 2—90)

This invention relates to garments and has for the primary object the provision of a device which will afford maximum warmth to the body of the wearer, comfort and freedom of movement and which may be worn either closed or open with attractive and neat appearance.

Another object of the invention is the provision of a garment which includes front portions which may be worn in overlapped relation and detachably secured on the waistband of the garment at the opposite sides of said garment or worn in turned back position and fastened on the garment at the sides of the waistband, providing at the front of the garment a V type opening extending to the waistband and further providing draped lapels giving the garment an attractive appearance.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a front elevation showing a garment constructed in accordance with the present invention and showing the front portions arranged in overlapped relation and secured at opposite sides of the waist band.

Figure 2 is a front elevation illustrating a garment with the front portions folded back and fastened at opposite sides of the waist band providing draped lapels on the front of the garment and a V-shaped opening extending from the neck portion to the waist band.

Figure 3 is a front elevation showing one of the front portions detached.

Figure 4 is a rear elevation, partly in section, showing the waist band and fasteners thereon.

Figure 5 is a front elevation showing a garment equipped with sleeves.

Referring in detail to the drawing, the numeral 1 indicates a garment which may be of the sleeveless type, as shown in Figures 1 to 4, inclusive, or have sleeves, as shown in Figure 5. The garment 1 consists of front portions 2 and 3, a back portion 4, a neck portion 5, armholes 6 and a waist band 7. The back portion 4 and neck portion 5 are tailored to have a form fit and the front portions 2 and 3 are cut to be form fitting and provided with overlapping extensions A, as shown in Figures 1 and 3. The extensions may be folded back upon their respective front portions to provide draped lapels, as shown in

Figure 2, and providing in the front of the garment a V-shaped opening extending from the neck portion 5 to the waist band. The waist band has separable fasteners 8 for securing the waist band closed as shown in Figure 2 with a tight fit about the waist of the wearer leaving end portions of the waist band, indicated by the character B, free. The end portions B are secured on the extensions A of the front portions. Buttons 9 or other similar fasteners are secured on the waist band at opposite sides of the garment and the portions B of the waist band have buttonholes 10 at their free ends. The buttons 9 and buttonholes 10 permit the fastening of the end portions B onto the waist band at the sides of the garment either with the extensions A of the front portions overlapped, as shown in Figures 1 and 3, or folded back upon the front portions, as shown in Figure 2, to provide the garment with draped lapels and a V-shaped opening in the front of the garment.

It will be seen from the drawing that when the garment is worn, as shown in Figure 1, the front portions overlap and are firmly fastened in position so that the garment will have a neatly closed and tailored appearance. However, when desiring to wear the garment as shown in Figure 2, the end portions B are folded back upon the waist band and secured at the sides of the garment by passing the buttons 9 through the buttonholes. The end portions B of the waist band thus fastened onto the waistband fold the extensions A back on the front portions providing to the garment at the front thereof draped lapels and the V-shaped opening extending from the neck portion to the waist band where it is closed by the fasteners 8.

The waist band is preferably constructed of an elastic material while the remaining portion of the garment may be made of any material suitable for the purpose. When the sleeves are employed on the garment, as shown in Figure 5, it is preferable that said sleeves have cuffs 11 of some suitable material having elasticity.

While the drawing in some places thereon shows the use of buttons and buttonholes on the garment, it is to be understood that other types of fasteners may be employed.

What is claimed is:

1. A garment comprising a jacket body including neck, back and openable opposite front portions, said front portions each having an extended tapering lower corner part to be brought forwardly into overlapping relation to the complementary correspondingly tapered corner part of

the opposite front portion of the jacket body and to be folded back on its own front portion to form a substantially triangular lapel, a waistband secured to and carried by said back and front portions of the jacket body at the bottom thereof and extending entirely between the frontal corner ends of the garment, separable fastener means on said waistband equidistant inwardly from the opposite ends thereof to secure the intermediate portion of the waistband encircled about the waist of the wearer with the outer portions of the waistband beyond said fastener means and carried by said extended corner parts of the front portions free of attachment to each other, and means for securing said free portions of the waistband at opposite sides of the garment either in forwardly overlapped relation with the adjacent front portions of the jacket body correspondingly overlapped and forming a relatively short V-shaped opening adjacent the neck portion of the garment or in folded back relation on the waistband to bring said parts of the front portions into folded position therewith to provide draped lapels on said front portions and a longer V-shaped opening between said front portions extending from the neck portion of the jacket body to the waistband.

2. A garment comprising a jacket body including a neck, back and openable opposite front portions, an elastic waistband secured on the back and front portions, separable fasteners carried by said waistband inwardly from its opposite ends for securing the band in an encircling condition and providing free end portions capable of being folded back on the waistband or brought forwardly in overlapping relation thereon, at will, fasteners for securing the end portions of the waistband in either the said folded back or for-

wardly overlapped relation on the band at opposite sides of the jacket body, said front portions of the jacket body being each shaped to provide them with extended tapered flap parts movable with the attached end portions of the waistband whereby to be placed either in forwardly overlapping relation to the adjacent opposite front portion of the jacket body or to be folded back on their own front portions to provide draped lapels therewith and a V-shaped opening in the jacket body extending from the neck portion thereof to the waistband.

3. A garment comprising a jacket body including a neck, back and openable opposite front portions, said front portions being each of a 15 shape to provide an extended tapered lower corner part to be brought forwardly into overlapping relation to the complementary correspondingly tapered corner part of the opposite front portion of the jacket body and to be folded back 20 on its own front body portion so as to form a substantially triangular lapel, a waistband secured to and carried by the back and front portions of the jacket body at the bottom thereof and extending entirely between the frontal corner 25 ends of the garment, separable fastener means on said waistband equidistant inwardly from the opposite ends thereof for securing the intermediate portion of the waistband encircled about the waist of the wearer with the outer portions 30 of the waistband beyond said fastener means free of attachment to each other, and means for detachably securing the ends of said free portions of the waistband in either forwardly overlapped or folded back relation on said waistband on opposite sides of the jacket body.
